United States Patent Office

Des. 183,437
Patented Aug. 26, 1958

183,437

CHAIR

Herbert E. Williams, Temple, Tex.

Application May 14, 1957, Serial No. 46,168

Term of patent 14 years

(Cl. D15—1)

FIG. 1.

FIG. 2.

Figure 1 is a perspective view of a chair embodying my new design;

Figure 2 is a top plan view thereof;

Figure 3 is a rear elevational view thereof;

Figure 4 is a side elevational view thereof; and

Figure 5 is a bottom plan view thereof.

The dominant features of the design are shown in full lines.

I claim:

The ornamental design for a chair, substantially as shown and described.
